YARN PROCESSING DEVICE**Goffredo Severini, Milan, Italy, assignor to Studi E Brevetti Applicazioni Tessili S. r. l., Milan, Italy****Application March 20, 1953, Serial No. 343,734****Claims priority, application Italy April 5, 1952****16 Claims. (Cl. 68—205)**

This invention relates to a device for continuously processing textile filaments, yarns and threads. In particular the device serves to carry out those treatments in which liquid agents, such as solutions of chemicals, wash waters, finishing preparations and the like are applied to the thread and which may be called "wet treatments" or "wet processing steps."

To carry out such treatments continuously, the thread is ordinarily wound on a thread-storing thread-advancing device, which causes the thread to travel in a substantially helical trajectory, that is a spiral-like line consisting of a plurality of successive turns, the precise geometrical shape of which depends on the particular structure of the thread-storing thread-advancing device that is employed.

Thread-storing thread-advancing devices, to be satisfactory must store a sufficient length of thread to allow all of the desired treatments to be efficiently effected and at the same time must have a limited bulk. Further, they should render possible a perfect separation of the various processing liquors applied to the thread which should not contaminate one another in order that they may conveniently be re-cycled and recovered.

Further, said devices must be easily operated and particularly easily threaded up, both at the start of their operation and whenever the thread breaks.

One class of thread storing and advancing device comprises a processing roller divided into several zones corresponding each to one wet or dry treatment, and an advancing roller askew to the processing roller, to cause the thread wound about both rollers continuously to advance along a substantially helical path when the rollers rotate.

It has been already proposed to separate the various wet processing zones by means of flanges or the like, collecting the liquors that drip from the processing roller in a trough divided into cells corresponding each to a wet processing zone.

In such devices, however, thread guides must be provided to guide the thread over the separation flanges and each guide determines an angle in the trajectory of the thread, causing a friction which may be particularly undesirable when the thread is still incompletely coagulated.

The threading-up of such devices may be effected by forming a ring or "cake" of thread about both rollers and by allowing it to advance along the device. However, when the ring contacts the first flange, it stops there and must be passed over the flange and engaged with the respective thread guide, either by means of complicated and impractical mechanism or by a manual operation which may be effected only if every point of the device is easily accessible.

One object of this invention is to provide a thread-storing thread-advancing device of the class described wherein the processing liquors are separated, even when used in large amounts, as effectively as by the use of flanges, and yet no angles are created in the trajectory of

2

the thread and no manual operations or mechanisms are required for the threading-up. Another object is to provide a device wherein the lengths of the several processing zones and even their number can be easily varied.

5 Other objects of the invention will appear as the description proceeds. According to the invention, the separation elements between the several wet-processing zones consist of belts of a suitable flexible material engaging the periphery of the processing roller along a sufficiently extended arc, preferably an arc corresponding at least to that portion of said periphery which is wetted by the processing liquors. Other rotatable supporting means, such as an auxiliary roller or a plurality of pulleys, are provided to cooperate with the processing roller to support the belts in a particular position that will now be geometrically defined.

We shall call "supporting surface" the simplest surface on which the trajectory of the thread, in the storing and advancing device, entirely lies: actually the supporting surface comprises a portion of the periphery of the processing roller (that portion which is contacted by the thread), a like portion of the periphery of the advancing roller, and two portions of ruled surfaces the generators whereof are tangent, on one and on the other side respectively, to the two rollers. It is to be noted that the expression "supporting surface" and its definition are purely geometric in character and the word "supporting" does not imply any material support. Now, the separation belts are tangent to the supporting surface at 15 the periphery of the processing roller, while elsewhere they are at least in part and may be wholly external thereto; at any rate, they never intersect such surface. The ratio between the portion wherein belts and supporting surface contact each other and the portion wherein 20 no such contact exists, may vary according to cases. The word "external" further does not imply any considerable distance between the belts and the supporting surface, while on the contrary even a very small distance and along a small portion of the belts may suffice. It has 25 been found—a fact that could not be foreseen and is surprising—that in these conditions the thread insinuates itself between the belts and the processing roller and proceeds in its travel practically as if the belts themselves did not exist, though said belts are wholly effective as separation elements between the several liquors.

30 In order to support the belts in the desired position the supporting means hereinbefore mentioned should be farther away from the processing roller than the advancing roller, and preferably in the same general direction. They should rotate about axes parallel to that of the 35 processing roller so that the belts, while taking part in the rotation of the processing roller, may not advance along the device.

The invention will be better understood with reference to the appended drawings which illustrate some embodiments thereof, wherein:

Fig. 1 is a perspective representation of a part of a device according to a first embodiment of the invention;

Fig. 2 represents the device of Fig. 1 seen from one end;

Fig. 3 is a sectional view at a larger scale of a detail of a second embodiment;

Figs. 4 and 5 are similar to Figs. 1 and 2 respectively, but illustrate a third embodiment;

Fig. 6 is a lateral view of a detail of a fourth embodiment;

Fig. 7 is a lateral view of a detail of a further embodiment;

Fig. 8 is a sectional view at a larger scale of a detail of another embodiment of the invention; and

Figs. 9, 10 and 11 are lateral views of details of a further embodiment of the invention,

With reference now to Figs. 1 and 2, numeral 10 represents a thread of any kind which, by way of example and as a particular application of the invention, may be considered to be a viscose rayon thread composed of a bundle of filaments originating from a single spinning nozzle and which travels in the direction of the arrows.

As it is known, in the case of viscose rayon, it is necessary, in order to obtain a finished product, to effect a series of wet treatments, for instance in timed succession, setting, first washing, desulphurizing, second washing, bleaching, third washing and finishing, followed by drying and possibly by conditioning, and other treatments may be added to those listed above, or some of those may be omitted. The actual number of the wet processing steps has been left undetermined in the drawings because the invention does not depend on such number and is applicable to any succession of treatments and also to threads different from viscose rayon and to different processing stages, and the first three processing zones and the beginning of the fourth zone only have been indicated since this is sufficient to a schematic illustration of the invention.

The thread storing and advancing device illustrated, comprises a processing roller 12 and an advancing roller 13 askew thereto. The device also comprises an auxiliary roller 14 having its axis parallel to the axis of processing roller 12.

The thread 10 winds up in a succession of turns in a substantially helical configuration about rollers 12 and 13. To each wet processing step there corresponds a processing zone on processing roller 12; zones 15, 16 and 17 have been completely indicated. The separation between the several zones is achieved by means of separation belts such as 18, 19 and 20, which embrace roller 12 and auxiliary roller 14. These belts are made of a sufficiently elastic material, for instance rubber or a synthetic material (vinyl, polyethylene, polyamide resins, etc.). In the embodiment of Figs. 1 and 2, the belts have a rectangular cross section, but such section is not prescribed, indeed, often is not the most suitable, as will be explained later. Due to the relationship of rollers 12 and 14, the belts theoretically do not have any tendency to progress longitudinally of the device, while the thread on the contrary so advances. However it is not generally possible, or at any rate it is not practical, to achieve and maintain as time goes on an absolutely parallel relationship of the roller axes, so that the belts may have or may acquire with time a tendency, no matter how slight, to shift along the rollers. Therefore, guides may preferably be provided for preventing any longitudinal displacement of the belts, and said guides may simply consist in forks like forks 21, 22 and 23 which straddle belts 18, 19 and 20 and hold them in a longitudinally fixed position.

The processing liquors may be fed to the processing roller 12 by any convenient means, for instance, through conveniently located pipes 24, 25, 26 etc. The processing roller is slanted with respect to the horizontal in such a way as to cause the liquors which form a film thereon, to move in a direction opposite to the travel of the thread, thereby to create a counter-current effect: therefore the thread advances from the lowermost end (in Fig. 1, the left end), to the uppermost end of roller 12. The liquors which drain from roller 12 are collected, to be re-used later, in separate vessels conveniently consisting of a single trough 27 (three walls of which are shown as broken off in the drawing) divided into separate cells, corresponding each to one processing liquor, by means of partitions like partitions 28, 29 and 30. In the embodiment of Figs. 1 and 2, any mixture of different liquors is avoided by locating each partition immediately before (with respect to the travel of the thread—that is, in Fig. 1, to the left) of the corresponding belt. If the liquor feed organs like 24, 25 and 26 are sufficiently displaced with respect to the belts so that the

liquor coming from each of them does not wet the belt which is located after (to the right of Fig. 1) said feed organ, any mixing of processing liquors is avoided. To that end, however, other means and combinations of parts, to be later described, may be adopted. Auxiliary roller 14 is located at a greater distance from processing roller 12 than advancing roller 13 and in the same general direction so that the separation belts remain external to the helical trajectory of the thread and the supporting surface thereof already geometrically defined, whenever they do not engage the processing roller, and at any rate never intersect such surface; obviously the belts engage roller 12 along an arc that is slightly narrower than the contact arc of the thread with said roller. Under these conditions the surprising fact is observed that the thread passes between the belts and the surface of roller 12 and travels undisturbed as if the belts—which, however, are effective in separating the processing liquors—did not exist as far as the thread is concerned.

This is schematically illustrated in Fig. 3 wherein a belt 31 having particular cross-section is shown. The thread 10 passes in a succession of turns between said belt and roller 12. Of course the dimensional relationships have been altered in Fig. 3 for purposes of illustration: in reality, no real gap exists between belt and roller, on the contrary, the belt is kept taut to prevent the liquors from infiltrating between it and the processing roller. The tension of the belt also exerts a beneficial squeezing action on thread 10. It has also been found—and this is even more surprising—that not only do the separation belts permit the advancement of the turns of thread, but that they also permit the advancement of the relatively thick ring of thread that is formed when the device is threaded up. Said threading-up is effected by winding a certain number of turns of thread about rollers 12 and 13 to form a ring or "cake" of thread which is then allowed to advance freely from the initial to the final end of the device; it is during the travel of these rings that the yarn arranges itself in a succession or substantially helical turns. It is seen therefore that in this way the threading-up of the device becomes very simple and it is not necessary that the various portions thereof—with the exception of the near end, that is the end adjacent to the spinning nozzle—be accessible either for manipulation or through mechanical means.

The invention may also be carried into practice by guiding the separation belts in a manner different from that indicated above, while maintaining the same geometric relationship between said belt and the thread path.

One particularly simple means, differing from that of Figs. 1 and 2, is illustrated in Figs. 4 and 5. Only the first two belts 33 and 34 are shown therein, and said belts are guided each by processing roller 12 and by a small pulley 35 and 36 respectively. If said pulley is grooved, the belt cannot become longitudinally displaced and all auxiliary guides of the type of forks 21 to 23 of Fig. 1 may be omitted. However the belts may be guided, no departure from the scope of the invention would be involved in introducing other rollers or, pulleys or auxiliary guide means, thereby causing the belts to assume a configuration differing from that illustrated and more complex, even if in such a manner the separation between the belts and the supporting surface should increase or decrease even to a very considerable extent.

In any case, the invention makes it possible to achieve another noteworthy new result, that is to vary the length of the various processing zones without substituting any parts of the device and even, in certain cases, while the device is in operation. This can be easily done, for instance in the embodiment of Figs. 1 and 2 by slidably mounting forks 21, 22, 23 etc. on a single support, such as a rod 37, and by fixing said forks by means of set screws 55, 56, 57 etc. or other means that are too obvious to require illustration, in any desired position on said support; or in the embodiment of Figs. 4, 5 and 6

by mounting each pulley 35, 36 etc. in such a way that it may longitudinally slide over a shaft 38 that is the same for all pulleys or on a separate shaft for each pulley, for instance by guiding the pulleys by means of keys 58, 59, etc., which engage corresponding key ways in the pulleys, then locking the pulleys in the desired position by means of set screws 61, 62, 63 etc. or the like. Convenient mechanical means may be used to displace the forks or pulleys even while the device is in operation, if this is required.

A proper choice of the cross-section of the separation belts may be very important to the end of perfectly separating the processing liquors. Fig. 3 shows one particularly efficient cross-section; the belt 31 is provided therein with two projections 40—40' having the character of flanges which define a central groove 41. The partition 42 of a trough 43 similar to trough 27 of Fig. 1, or at any rate the wall of a collecting vessel for the processing liquor which corresponds to the particular separation belt under consideration, faces groove 41. Under such conditions the liquor coming from the right in Fig. 3 will be stopped by projection 40' and will drain from roller 12 into the vessel or cell to the right of partition 42. It will not be necessary to make sure that the liquor coming from the left in the drawing should not reach to the separating belt (as it was advisable to do in the case of rectangular rings as in Fig. 1); on the contrary, one may conveniently allow said liquor to wet the entire processing zone belonging thereto, inasmuch as projection 40 will take care of stopping said liquor coming from the left of belt 31 and cause it to drain from roller 12 into the vessel or cell to the left of partition 42. Obviously the particular cross-section indicated in Fig. 3 is not essential, and grooved separation belts may be made with different shapes, or two simple belts may be placed close to each other so as to leave a gap therebetween wherein partition 42 or the like will extend or which said partition will face, or more grooves or gaps may be defined, or any shape or combination of parts according to the same principle may be adopted.

Fig. 6 shows an embodiment wherein the belts have the shape of Fig. 3 and are mounted on grooved pulleys as in Figs. 4 and 5.

Fig. 7 shows a sectional lateral view of an embodiment of the device wherein separation belts 45 (three of which are shown) are provided each with two projections 46—47 and are laterally guided by forks 48, similar to the forks 21—22—23 of Fig. 1, each mounted on a sleeve 49 laterally slidable on a guide shaft 50 and provided with a set screw 51. The liquor collecting vessel generally indicated at 52, is divided into cells by partitions 53, and each partition 53 faces a recess 54 between the two projections 46—47 of a separation belt 45.

Fig. 8 shows by way of example another cross-section that may be adopted for the separation belts, therein identified by numerals 80, 81.

Fig. 9 shows a similar embodiment, wherein, however, the belts 45 (only one of which is shown) instead of being passed about the processing roller 12 and an auxiliary roller 14 as in Fig. 7, are passed about the processing roller 12 and grooved pulleys, such as pulley 60, wholly analogous to pulleys 35—36 of Fig. 4, but provided, instead of with set screws, with an additional groove 66 which is engaged by the end of a lever 67 having a slot 68 which engages a pivot 69 fixed to the frame of the machine. The lever 67 is provided with a handle 70 for actuating it, and in swinging about pivot 69, it actuates the pulley 60 longitudinally of a shaft 71 on which it is slidably supported. In this manner the belt 45 can be adjusted longitudinally of the device as desired.

The liquor collecting vessel is wholly analogous to the vessel of Fig. 11.

Fig. 10 shows a further embodiment of the device in which the separation belts are provided in pairs, each pair

separating two adjacent processing zones of the processing roller. In the drawing only one of such pair of belts, 72—73, is illustrated. The two belts are supported by processing roller 12 and by an auxiliary roller 14, and they are so arranged that a partition 74 of the liquor collecting vessel 75 directly faces and projects into the gap between the two belts 72—73. Each belt is longitudinally guided by a fork 76—77. Each pair of said forks is mounted on a sleeve 78 slidable on a guide shaft 79. Sleeve 78 is connected by a link 80 suitably supported as schematically indicated at 81, to a couple of screws 81—82 actuated by hand through the handle 83. By turning handle 83 sleeve 78, and therefore the two forks mounted on it, are slid longitudinally of the processing roller to adjust their axial position.

Fig. 11 shows a still further embodiment of the device. The processing zones are separated from one another by pairs of belts 92—93 wholly analogous to the pair of belts 72—73 of Fig. 10. Said pairs of belts, however, are supported by processing roller 12 and each by a double grooved pulley 94 provided with set screws 95 to fix its position longitudinally of a supporting shaft 96. Liquor collecting vessel 97, like vessel 75 of Fig. 10, has its partitions 98—99 facing and projecting each into the gap between two adjacent belts 92—93.

What I claim is:

1. Device for the continuous wet processing of textile filaments, yarns and threads, comprising, in combination with a rotatable processing roller having a plurality of processing zones corresponding to the several thread processing steps and a rotatable advancing roller askew to said processing roller for advancing the thread in a substantially helical trajectory, a plurality of separation belts engaging the periphery of said processing roller each at the borderline of two adjacent processing zones, and rotatable belt supporting means peripherally engaged by said belts and cooperating with said processing roller rotatably to support said belts, said supporting means being positioned farther away from said processing roller than said advancing roller whereby said belts at no point intersect the thread supporting surface.

2. Device according to claim 1, wherein the belt supporting means are positioned with respect to the processing roller in the same general direction as the advancing roller.

3. Device according to claim 1, wherein the arc along which the separation belts engage the processing roller is large enough for said belts effectively to separate the processing liquors applied to the thread in adjacent processing zones.

4. Device according to claim 1, wherein the separation belts are mounted under tension to facilitate the effective separation of the processing liquors applied to the thread in adjacent processing zones.

5. Device according to claim 1 wherein the axis about which the belt supporting means are rotatable is parallel to the axis of the processing roller.

6. Device according to claim 1 comprising belt guides for preventing displacements of the separation belts parallel to the axis of the processing roller.

7. Device according to claim 1, wherein the separation belts are substantially triangular in cross-section.

8. The combination of a device according to claim 1, and a plurality of stationary cells located below the processing roller for collecting the processing liquors that drip from the several processing zones of the processing roller, each cell being so positioned as to receive only the liquor that drips from one processing zone.

9. Device for the continuous wet processing of textile filaments, yarns and threads, comprising in combination with a rotatable processing roller having a plurality of processing zones corresponding to the several thread processing steps and a rotatable advancing roller askew to said processing roller for advancing the thread in a substantially helical trajectory, a plurality of separation belts en-

gaging the periphery of said processing roller each at the borderline of two adjacent processing zones, and a rotatable auxiliary roller parallel to said processing roller and at a greater distance therefrom than said advancing roller, said auxiliary roller cooperating with said processing roller to support said belts in a position wherein they at no point intersect the thread supporting surface.

10. Device according to claim 9, comprising belt guides engaging the separation belts to prevent any displacements thereof parallel to the auxiliary roller.

11. Device according to claim 9, comprising belt guides for preventing displacements of the belts parallel to the auxiliary roller, and means for shifting said guides along said roller.

12. A yarn processing device comprising a processing roller, a row of liquor receiving cells positioned under said processing roller, partitions separating said cells from one another, a rotatable advancing roller askew to said processing roller for advancing the threads along the processing roller in a generally helical path, a plurality of separation belts, auxiliary rotatable belt supporting means, said belts passing around said processing roller adjacent the said partitions and around said auxiliary belt supporting means, belt guides for retaining said belts in position, said auxiliary belt supporting means being positioned beyond said advancing roller so that the belts will not interfere with the advance of the yarn along said processing roller.

15

20

25

13. Device according to claim 12, wherein the auxiliary belt supporting means are grooved pulleys having their axes substantially parallel to that of the processing roller.

14. Device according to claim 12, wherein the separation belts are provided with at least two proections which determine at least one intermediate groove.

15. Device according to claim 12, wherein the separation belts are provided with at least two projections which determine at least one intermediate groove located, on the outer side of each belt and wherein the liquor receiving cells are defined by partition walls and a partition wall between two collecting cells is positioned directly below each of said grooves located on the outer side of the separation belts.

16. Device according to claim 12, wherein the auxiliary rotatable belt supporting means are pulleys having their axes parallel to the axis of the processing roller, and further comprising means for shifting said pulleys parallel to said processing roller.
